United States Patent Office.

EVERETT P. RICHARDSON, OF LAWRENCE, MASSACHUSETTS.

Letters Patent No. 65,120, dated May 28, 1867; antedated May 16, 1867.

IMPROVEMENT IN BOOTS AND SHOES.

The Schedule referred to in these Letters Patent and making part of the same.

TO ALL WHOM IT MAY CONCERN:

Be it known that I, EVERETT P. RICHARDSON, of Lawrence, in the county of Essex, and State of Massachusetts, have invented a new and useful improvement in the "Manufacture of Boots and Shoes;" and I do hereby declare that the following is a full and exact description of the same, reference being had to the accompanying drawings, making a part of this specification.

Figure I is a perspective view of a part of a shoe.

Figure II represents the wire from which nails are made.

Figure III represents a barbed nail or peg.

Figure IV represents barbed and corrugated nails with heads.

My improvement in the manufacture of boots and shoes relates chiefly to the attachment of the sole to the upper leather, the fastening being effected by the use of barbed or serrated nails or pegs, both with and without heads. By this mode of nailing, the parts are closely held together, and on account of the firm hold of the nails in the leather a less number is required, and the sole of a shoe thus fastened is stronger than it is when a close row or series of pegs is used.

In Fig. I both kinds of nails are represented. Those marked A are straight barbed pegs or nails; those marked B are barbed and also provided with heads C. The upper leather of the boot or shoe is seen at D, the sole at E, and the insole at G. Between the two soles is the filling H. When a shoe is to be made by the use of the headed nails, as shown in Figs. I and IV, the nails are first inserted in holes previously punched in the insole G, the insole is then laid upon a last faced with iron, the heads of the nails resting upon the iron, which serves as an anvil. The upper leather D is then drawn over and formed around the last, and its edges turned inward upon the points of the nails. A few blows with a mallet forces the upper leather on to the nails. The outer sole E is then laid upon the points and the sole driven down, causing the nails to enter and hold the upper fast between the two soles. The headed nails above referred to may be either barbed or corrugated as represented in Fig. IV. The insole may be dispensed with, when desirable, in which case the nails are first inserted in the uppers, then drawn upon the iron last and the sole driven down upon the nails, as before mentioned. The headless barbed or corrugated nails A, Fig. III, are driven in the usual manner, entering the outer sole E first, then passing through the upper leather D and entering the insole G. These nails are usually made of round brass or iron wire, by passing the wire through suitable grooved or serrated steel rollers, or by notching or nicking it upon opposite sides, in any convenient manner, leaving wire in the form shown in Fig. II, ready to be cut into suitable lengths to form pegs or nails. Instead of notching the wire and raising a short barb, I sometimes prefer to corrugate or slightly bend the wire back and forth, the central line or axis of the wire being straight. The pegs or nails may be made of brass, iron, steel, or any other metal that has the requisite strength and stiffness.

What I claim, and desire to secure by Letters Patent, is—

The system or mode of fastening the soles of boots and shoes, by means of barbed or corrugated nails or pegs, either with or without heads, and driven either from the outside or inside of the boot or shoe, substantially as herein set forth and for the purpose specified.

E. P. RICHARDSON. [L. s.]
